UNITED STATES PATENT OFFICE.

JAMES J. JOHNSTON AND HAROLD McCaULEY, OF SHAW, WEST VIRGINIA.

RAIL-CHAIR.

1,259,870.

Specification of Letters Patent. Patented Mar. 19, 1918.

Application filed July 11, 1917. Serial No. 179,907.

To all whom it may concern:

Be it known that we, JAMES J. JOHNSTON and HAROLD McCaULEY, citizens of the United States, residing at Shaw, in the county of Mineral and State of West Virginia, have invented certain new and useful Improvements in Rail-Chairs, of which the following is a specification.

This invention relates to rail chairs, and 10 it more particularly relates to what we prefer to call our improved boltless rail plate.

It is well known that a very considerable amount of the trouble, expense and danger, consequent to the continual tendency of rail-way rails to become loosened from their seats, arises from the fact that the bolts and nuts thereof are continually working loose. It is also well known that there is a considerable amount of expense attached to making holes through the rail webs for the accommodation of bolts. Therefore, one of the main objects of the invention is to provide a rail plate or chair which holds the rail securely against lateral movement, without the use of bolts through the web of the rail.

Another object is to provide a rail chair of which one of the flange-engaging elements is pivotally or hingedly connected to 30 the adjacent one of the flange-engaging elements, so that these two elements may be engaged with the rail flange very quickly and easily, and hold the flange with unfailing security when thus engaged.

Other objects and advantages may become apparent to persons who read the following detailed description in connection with the accompanying drawings, in which:

Figure 1 is a top plan view illustrating a 40 section of a railway rail secured in place by means of our improved rail chair or plate;

Fig. 2 is a side elevation view of the structure illustrated in Fig. 1; and

Fig. 3 is an end view of the section of rail 45 and of the rail chair or plate which supports the rail.

Referring to these drawings in detail, in which similar reference characters correspond to similar parts throughout the several views; the rail 10, being no part of this invention, is not described in detail, and the same is true of the railway ties 11.

Our improved rail chair comprises the horizontal plate or lower flange-engaging member 12, a stationary upper flange-engaging member 13, a movable flange-engag-

ing member 14, a web-engaging member 15 and hollow brace blocks 16 and 17.

The plate or lower flange-engaging element 12 is formed integrally with the 60 flange-engaging element 13 and one of the web-engaging elements 15, while the movable flange-engaging element 14 is pivotally or hingedly secured at 18 to the edge of the plate 12 which extends laterally beyond one 65 of the rail flanges a sufficient distance to allow bolts 19 to extend between the rail flange and the pivot 18.

The block 16 is provided with a U-shaped extension at 20 which extends over the 70 flange-engaging element 14 and under the flange-engaging element 12, so as to fit these elements snugly when they are engaged with the rail flange. The U-shaped element 20 is provided with pairs of axially aligned 75 bores through each pair of which one of the bolts 19 extends. Each bolt 19 is fitted with a nut 21, and the bolts and nuts 19 and 21, when screwed up, draw the sides of the U-shaped member 20 against the respective 80 lower and upper flange-engaging elements 12 and 14, thereby clamping the contiguous flange securely, and at the same time pressing the element 16 against the element 15 and thereby pressing this element 15 against 85 the rail web. It may be desirable to supplement the bolts 19 by means of bolts 22, and when these bolts 22 are employed, it may be found expedient to provide apertures or 90 notches in the contiguous rail base, and to provide apertures in the elements 12 and 14 for these bolts to extend through.

The brace block 17 is provided with a laterally extending flange 23 which is apertured for the reception of bolts 24, the elements 12 and 13 also being apertured, and the rail flange being recessed, so that the bolts 24 extend therethrough. These bolts are provided with nuts 25 which coöperate with the bolts for securely clamping the elements 12, 13 and 23 together, and at the same time forcing the element 17 against the contiguous element 15.

It will be seen that the lower portion of the U-shaped element 20 extends between the ties, so as to avoid interference therewith, and it will also be seen that this device is provided with notches 26 and apertures 27 through which any ordinary or desired form of rail spikes 28 may extend.

From the foregoing, it is evident that we have provided a rail chair which is exceed-

ingly useful, practicable and efficient, and which is believed to fill the long felt need of a device of this character.

We claim:

- 5 1. A rail chair comprising a plate or rail seat, a combined flange-engaging and web-engaging element, a hinge connecting said rail seat with the combined flange-engaging and web-engaging element, a substantially 10 U-shaped element normally fitted around said hinge and embracing said rail seat and combined flange-engaging and web-engaging element, and means for securing said U-shaped element in its normal position.
- 15 2. The combination of a rail seat, a combined flange-engaging and web-engaging

element, a combined brace block and clamping element, said clamping element being substantially U-shaped and being apertured, and means extending through the apertures 20 of said U-shaped element for causing the latter to press said rail seat and said combined flange-engaging and web-engaging element against the flange and web of a rail when the latter is seated on said rail seat. 25

In testimony whereof we affix our signatures in presence of two witnesses.

JAMES J. JOHNSTON.
HAROLD McCUALEY.
